APPARATUS FOR MILLING SOLID PARTICLES WITHIN A LIQUID SLURRY

Edward J. Szkaradek, Santa Ana, Samuel Arthur Skeen,
Jr., Claremont, and John J. Corrigan, Garden Grove,
Calif., assignors to Morehouse Industries, Inc., Fullerton,
Calif.

Filed July 9, 1975, Ser. No. 594,191

Term of patent 14 years

Int. Cl. D15—99

U.S. Cl. D15—122

Fig. 2

Fig. 3

FIG. 4.FIG. 1 is a perspective view showing the top, left, and front sides of the apparatus design;

FIG. 2 is a right side elevational view of the apparatus design;

FIG. 3 is a bottom view of the apparatus design; and

FIG. 4 is a rear elevational view of the apparatus design.

I claim:

The ornamental design for an apparatus for milling solid particles within a liquid slurry, as shown.
